UNITED STATES PATENT OFFICE.

WALTER L. ALBER, OF CHICAGO, ILLINOIS.

ANCHOR.

Application filed April 24, 1925. Serial No. 25,498.

To all whom it may concern:

Be it known that I, WALTER L. ALBER, a citizen of the United States, and a resident of Chicago, Cook County, Illinois, have invented an Improvement in Anchors, of which the following is a specification.

This invention relates to anchors and with regard to certain more specific features to anchors for sleepers or studdings which abut against concrete or other once plastic material.

Among the several objects of the invention may be noted the provision of a simple, rugged, and inexpensive, one-piece anchor, adapted to be flat until put into use, and adapted to be readily laid and accurately aligned when used in numbers.

The invention accordingly comprises the features of construction, combinations of elements, and arrangements of parts which are exemplified in the structure hereinafter described and the scope of the application of which will be indicated in the following claims.

25 In the accompanying drawings in which is shown one of various possible embodiments of the invention,

Fig. 1 is a front elevation of the anchor;

Fig. 2 is a top plan view of the anchor;

30 Fig. 3 is a side elevation of the anchor;

Fig. 4 is a plan view of the stamped blank from which the anchor is made, and shows in dotted lines the points at which formative bending is made to take place;

35 Fig. 5 is a side elevation showing a number of anchors fastened to an aligning board;

Fig. 6 is a cross section showing an anchor on its aligning board and sunk in concrete;

40 Fig. 7 is a view similar to Fig. 6 showing modified use of the device and an alternate position of the aligning board; and,

Fig. 8 shows the anchor buried in concrete and applied to a sleeper.

Referring now more particularly to Figs. 45 1 to 3 inclusive, there is illustrated at 1 a wedge or bridge comprising two limbs joined at a bent or creased portion 3.

The limbs each comprise a tapering web 5 and a pair of tapering flanges 7 formed integrally with and at right angles to said webs 5. The pairs of flanges of the two webs overlap at a point 9.

50 At the outer extremities of the limbs of wedge or bridge 1 are integrally formed substantially horizontal ears or plates 11.

The ears or plates 11 are provided with

pairs of fastening holes 13 and pairs of side notches 15. The holes 13 are adapted to receive nails or screws comparable in size to about a ten-penny nail. The notches 15 are adapted to receive said approximate size of nail loosely at the shank of the nail, but will not permit the passage of the flat head of such a nail.

At the ends of the ears 11 are provided 65 notches 17 comparable in size to the notches 15 but not formed so deeply from the edge of the material of the ear.

The manufacturing method used for making the anchor is simple. As illustrated in 70 Fig. 4 a flat blank is punched or otherwise formed out of a relatively light gauge of sheet metal embodying in its shape the features noted regarding the ears.

The flat ears are (as shown by the Fig. 4) 75 joined by means of a strip of flat sheet metal 19, notched centrally between said ears 11 and on both sides, with notches 21. So far, only a punching or other single forming operation has been required.

80 Next the flanges 7 are bent upwardly on the four dotted lines 23 shown in Fig. 4. These lines pass from the ends of the notches 21 and run to the edges of the strip 19 at its juncture with the ears. As stated, the device is made entirely of a single piece of material so that said juncture is not a joint.

85 The next operation is to bend the strip 19 at the dotted line 25 (Fig. 4) to form the limbs of the wedge 1. This bending operation involves overlapping the now formed flanges 7.

90 Simultaneously with the last named operation the ears 11 are bent into a single plane with one another along the dotted lines 27.

95 Finally the now flat ears 11 are given a slight upward concave curvature for purposes to be described.

100 To plant the anchors in concrete an alignment board is made up. This board comprises any suitable piece of planking 29 (Figs. 5 and 6) provided with sets or pairs of nails 31 driven not quite home in one side of the plank. The separate nails of a pair are spaced either the lateral distance apart of two of the notches 15 in opposite ears, or the lateral distance apart of the notches 17 in the opposite ears, depending upon the method of mounting to be used.

105 Figs. 5 and 6 show the former spacing and Fig. 7, the latter spacing. The longitudinal

spacing of the pairs may be arranged to suit the job in hand.

As stated, the nails are not driven home but have space beneath their heads 33 equal 5 approximately to the thickness of metal in the anchor.

- To mount anchors on the board, the preferred method to be used is to space the nails for the notches 15 as shown in Figs. 5 and 6.
- 10 The anchors are then slipped in under the heads 33 by placing the ears 11 flat on the board and causing a pair of the notches 15 to register with a pair of nails 31. The slightly concave surfaces of the ears 11 serve to give 15 them resiliency so that they may conform to various amounts of spacing which may be under the nail heads.

After having mounted upon the board, as many anchors as are required to hold a 20 sleeper, or as many as need be in a straight line, the board is laid down upon the wet concrete in which the anchors are to be mounted.

The wedges 1 are made to point down- 25 wardly. Next a workman or other person treads upon the board, thereby pressing the wedges 1 into the concrete. The pointed shape of the wedges serves to push and wedge aside stones, gravel, etc., which may 30 be encountered in the concrete mix.

Thus the anchors are driven into the concrete which flows in over the limbs of wedge 1. The under-surface of the board 29 prevents deformation of the concrete surface. 35 The flanges 7 serve to brace the limbs against deformation when hard masses are encountered, and their upwardly tapering shape (Fig. 6) prevents pulling out of the anchor from hardened concrete should the 40 limbs break apart at line 3 due to any cause whatsoever.

The anchors having been sunk into the concrete, all that is necessary to do in order 45 to remove the aligning board 29 is to push it longitudinally in the direction of the arrow shown in Fig. 5, that is, if the side notches 15 are used. If the anchors had been slipped in under the nails from the other side, that is, had the other pair of 50 notches 15 been used the motion of the board would have been in the opposite direction for removal.

Upon moving the board longitudinally 55 the heads of the nails are freed of the notches 15 and the board is free to be lifted and again used for aligning a new batch of anchors. The nails need not be removed or reset in the aligning board in order to be used as often as desired for the purposes 60 described.

The concrete of course hardens about the anchor and after a period of time a sleeper 35 (Fig. 8) may be placed over and between the ears 11. The ears are then turned vertically and fastened to the sides of the 65

70 sleeper by means of nails driven through the pairs of holes 13. Of course the dimensions of the anchor are adapted to fit the types of sleepers or studdings in use.

It is to be understood that the aligning board may be removed either while the concrete is wet or when it has dried. The resistance to motion through wet concrete offered by the flanges 7 is enough to keep 75 the anchors in place. Of course, if it is desired, the aligning board may be left with the anchors until the concrete dries after which said board may be removed as re- cited.

80 The alternate way for fastening the anchors to the aligning board is illustrated in Fig. 7. As shown the nails 37 are spaced a lateral distance apart equal to the lateral distance between the end notches 17 of the anchor. The nails are not driven home but 85 have, as before, a space under the head.

To mount the anchors one of the end notches 17 is registered under the head of 90 one of the nails 37. The limbs of the wedge 1 are then sprung together slightly and the other notch 17 permitted to register with the other nail 37. Upon releasing the wedge limbs, the registration of notches under the nail heads is completely accomplished be- 95 cause of the spring in the material of the anchor.

To force the anchors into the concrete the board is trod upon as before. To remove 100 the board from the anchors, embedded in either wet or dry concrete, it is only necessary to lift said board.

When the board is lifted the ears 11 bend 105 upwardly until the nail heads are able to clear the ends of the ears 11. The alternate position of the anchor ears shown in Fig. 8 is accomplished.

Immediately after the nails pass from in 110 under the ears 11, said ears spring back into their flat position on the surface of the concrete.

The anchor may now, as before be applied to a sleeper or other element by turning up the ears 11, and nailing them to said sleeper or element, by means of nails passed through holes 13.

115 There have been described herein, alter- nate ways for fastening the anchors to the aligning board and alternate ways for removing the board. These alternatives are incorporated in a single anchor so that a person setting the anchor may have a choice of mounting methods. This feature permits of a wide range of adaptability of the anchor.

120 The fact that the anchor, after planting or setting, lies flat until applied to a sleeper is of great advantage where objects and material are wheeled over a partly finished floor.

125 The single piece, wedge shape construc-

tion has obvious advantages herein related, and the aligning feature is of inestimable value where long rows of the anchors are to be used.

5 In view of the above, it will be seen that the several objects of the invention are achieved and other advantageous results obtained.

As various possible embodiments might be 10 made of the above invention and as various changes might be made in the embodiment above set forth, it is to be understood that all matter herein set forth or shown in the accompanying drawings is to be interpreted 15 as illustrative and not in a limiting sense.

I claim:

1. A one piece anchor for sleepers and the like comprising a bridge adapted to be sunk in a plastic composition and sidewardly extending ears thereon, means on said ears for detachably fastening the anchor to a device for laying the anchor with the ears flat, and means on said ears for permanently fastening the anchor to the sides of a 25 sleeper.

2. A one piece anchor for sleepers and the like comprising an upwardly flanged inverted bridge adapted to be sunk in a plastic composition and sidewardly extending ears 30 thereon, means on said ears for detachably fastening the anchor to a device for laying the anchor, and means on said ears for permanently fastening them to a sleeper.

3. An anchor for sleepers and the like 35 comprising an anchoring means, ears on said anchoring means, means on said ears for mounting said anchor on an aligning device and whereby the anchor may be freed of the aligning device by movement of the device when the anchor is set, said means comprising a bulge in the ears and notches therein by means of which the ears may be partially forced in under heads of nails partially driven into said aligning device.

4. A one piece anchor for sleepers and the like comprising a bridge adapted to be sunk in a plastic composition and sidewardly extending ears thereon, longitudinal upwardly tapering flanges thereon adapted to retain the anchor in position after laying although the bridge breaks, means on said ears for detachably fastening the anchor to a device for laying the anchor with the ears flat, and means on said ears for permanently fastening the anchor to the sides of a sleeper.

5. An anchor for sleepers and the like

comprising a body of wedge shape, sidewardly extending ears thereon, adapted to be flat until bent upwardly for fastening, 60 sideward notches in said ears adapted to slip in under the heads of partially driven nails in an aligning device and adapted to permit removal of the said device by relative longitudinal movement of the same.

6. An anchor for sleepers and the like 65 comprising a body of wedge shape, sidewardly extending ears thereon adapted to be flat until bent upwardly for fastening, lateral notches in said ears adapted to slip in under the heads of a pair of partially driven 70 nails in an aligning device, and adapted to permit removal of the said device by relative vertical movement of the same, thereby temporarily springing the ears from their flat position so as to pass between said nail 75 heads.

7. An anchor for sleepers and the like comprising a body of wedge shape, sidewardly extending ears thereon adapted to be flat until bent upwardly for fastening, sideward notches in said ears adapted to slip 80 in under the heads of partially driven nails in an aligning device and adapted to permit removal of the said device by relative longitudinal movement of the same, and lateral notches in said ears adapted to slip in under the heads of a pair of partially driven 85 nails in an aligning device, said lateral notches being adapted to permit removal of the said device by relative vertical movement 90 of the same, thereby temporarily springing the ears from their flat position so as to pass relatively downwardly between said nail heads.

8. A one-piece anchor for sleepers and the like, comprising a body of wedge shape adapted to be sunk in a plastic composition, upwardly tapered flanges on said wedge shaped body member, and sidewardly extending ears thereon.

9. An anchor for sleepers and the like comprising a body of wedge shape having lateral ears thereon, notches in the ears for temporarily slipping the ears in under partially raised heads of an aligning device and 105 holes in the ears whereby they may permanently be fastened to a sleeper by a connection through said holes.

In testimony whereof, I have signed my name to this specification this 17th day of April, 1925.

WALTER L. ALBER.
